Patented October 6, 1903.

UNITED STATES PATENT OFFICE.

ALICE H. KIMBERLING, OF POINT PLEASANT, WEST VIRGINIA.

DESIGN FOR A TOY MONEY-BANK CASE.

SPECIFICATION forming part of Design No. 36,579, dated October 6, 1903.

Application filed March 31, 1903. Serial No. 150,491. Term of patent 7 years.

To all whom it may concern:

Be it known that I, ALICE H. KIMBERLING, a citizen of the United States of America, residing at Point Pleasant, in the county of Mason and State of West Virginia, have invented a new, original, and ornamental Design in Toy Money-Bank Cases, of which the following is a specification, reference being had therein to the accompanying drawings.

This invention relates to certain new and original designs in a toy money-bank case.

In describing the invention in detail reference is had to the accompanying drawings, in which—

What I claim is—

The ornamental design for a toy money-bank case, substantially as herein shown.

In testimony whereof I affix my signature 20 in the presence of two witnesses.

ALICE H. KIMBERLING.
